UNITED STATES PATENT OFFICE.

GARDNER A. GIBBS, OF LIVONIA, NEW YORK.

SEPARATOR.

SPECIFICATION forming part of Letters Patent No. 656,719, dated August 28, 1900.

Application filed March 14, 1898. Serial No. 673,839. (No model.)

To all whom it may concern:

Be it known that I, GARDNER A. GIBBS, a citizen of the United States, and a resident of Livonia, in the county of Livingston and State 5 of New York, have invented certain new and useful Improvements in Separators, of which the following if a specification.

My invention relates to that class of machines used for sorting beans, peas, and various grains and separating from them foreign substances, and has for its object to provide means for quickly and accurately accomplishing this separation.

In the accompanying drawings, Figure 1 is 15 a side elevation of the machine; Fig. 2, a top view; Fig. 3, a section on the line 3 3 of Fig. 2; Fig. 4, a section on the line 4 4 of Fig. 2, and Figs. 5 and 6 parts hereinafter to be described.

20 In the drawings is shown a machine illustrating my invention, in which A represents the main stationary frame of the machine, on which are supported the various parts. Within this main frame and pivoted to its end bars 25 A' A² by bolts b b', so as to be capable of transverse tilting, is a second frame composed of end pieces B B² and side pieces B' B³. A block b³ is shown (see Fig. 1) between the end piece B of said tilting frame and the cross-piece A³, 30 through which also the bolt b passes. The bolt b lies within a slot b⁴ in the cross-piece A³ of the stationary frame, (see Fig. 4,) so that this end of the tilting frame may be raised or lowered through the length of this 35 slot. The frame may be secured at the height desired by the nut b⁵, which is shown with a handle attached to it, by which it is operated. A handle-bar b⁶ is attached to the other end of the tilting frame and the bolt b' passed 40 through it and the cross-piece b³. Said handle-bar projects outward beyond the stationary frame in the manner shown in Fig. 1, affording means for tilting the frame. It may be secured in place by a nut b⁷ upon the bolt 45 b⁸, which latter lies in a slot in the post A⁴, which permits the adjustment. The slot is not shown in the drawings.

It is desirable that the frame B should be capable of both longitudinal and transverse 50 tilting in order that it may be adapted to the separation and grading of different objects,

some of which roll much more readily than others.

Secured upon shafts c c', which are transversely journaled in the side pieces B' B³ of 55 the tilting frame near its ends, respectively, are rollers C C'. Attached to the end of the shaft c' and extended beyond the stationary frame a crank c² is shown, with handle c³, by means of which the roller C' may be revolved. 60 The device can of course as well be driven by any other power, and suitable attachments therefor can be readily made for it. Between the rollers C C' and supported by the side piece B' of the tilting frame is a table D (see 65 Figs. 3 and 4) for the support of the endless belt E, which is passed around the said rollers and over said table. The upper surface of this endless belt constitutes a movable carrier on which the objects are separated in 70 the manner hereinafter to be described and from whose surface they are conducted when separation has taken place into distinct masses. Between the edge of this table and the side piece B³ of the tilting frame a space 75 b⁹ is left, as shown in Fig. 4.

Chutes E' E² are attached to the tilting frame in the position shown in Figs. 1 and 4. The upper edges of the inner faces of the said chutes are placed somewhat below the upper 80 side of the belt, (see Fig. 4,) and their outer surfaces are carried up above the lower edge of the side piece B³ of the tilting frame, as is shown in Figs. 1 and 4. Extending along the bottom of the table D and resting on the 85 top of the inner surfaces of the chutes E' E² is the inclined surface or platform F. (See Figs. 3 and 4.) A partition G (see Figs. 2 and 3) is placed across said platform F at a point between the chutes E E'. Attached to 90 the end of the tilting frame beneath the roller C is a third chute H, and above the belt and supported on the main frame A is a hopper K, provided with a gate or slide k, as indicated in Fig. 1, whereby beans are dropped in regulated quantity upon the belt. 95

The functions of the several parts will be clearly shown in the description of the operation of the machine found hereinbelow.

In my machine the separation is accomplished by spreading out or dispersing the beans upon the belt during their passage on

it, thus permitting the round most perfect beans to separate themselves from the mass and to roll off from the belt into receptacles placed to receive them, while the imperfect beans and refuse matter remain upon the belt and are carried to another chute through which they are discharged. By the device I employ the beans are repeatedly thus spread out and dispersed while on the belt, and the separation is thereby rendered very complete and thorough. To accomplish this, I place back and forth across the belt in zigzag order, alternately, beginning on the left beneath the hopper K, guides L and M. (See Figs. 5 and 6.) One end of each guide M lies within grooves in the side piece B', and the other end is set in a slotted block m, whereby the guides are retained in position. One end of the guides M also fits within notches l in the guides L, and the guides L in turn are slipped within one of the notches m' shown in the guides M. In this way the guides are fixed in place, the several notches shown in the guide M for the reception of the end of the guide L making it possible to change the angle of the guide L with reference to the line of movement of the belt. The lower ends of both guides are set close to the belt E; but the manner in which they are cut away (shown in Figs. 5 and 6) leaves passages through them near the upper and lower edges of the belt alternately, as shown by the arrows in Fig. 2.

The operation of this machine is as follows: 35 When the tilting frame has been set at the proper inclination and its lower end adjusted to the height desired, the belt is put in motion and the beans are allowed to fall from the hopper K upon the belt. They are carried on it along the first guide M' until they reach the passage shown by the arrows in Fig. 1, through which they pass. As they come out from the passage into the space N, between said guide M' and the next guide 40 L', they are dispersed across the belt. The round most perfect beans will then roll down the inclined surface of the belt and falling upon the guide-surface F beneath will be directed into the chute E'. The remaining 45 beans and the foreign substances mixed in with them will be carried forward by the belt and collected against the guide L', along which they will move to the next passage indicated by the arrow. The beans will be 50 carried along said guide L' in a thin line from which the round ones will soon easily separate themselves to roll down the belt. Entering the space N' they are carried up along the guide M² to the top of the belt again, to 55 be once more scattered across the belt, so that the round beans may roll off into the chute E'. The beans are thus carried successively to the spaces N', N², N³, N⁴, N⁵, N⁶, and N'. In the spaces N, N², N⁴, and N⁶ they 60 are spread across the belt, so that the round ones may roll down the inclined surface of

the belt, while on each of the spaces N', N³, N⁵, and N' they are carried back to the top of the belt, and the separation is facilitated during their passage along each of the succeeding guides L², L³, and L⁴. The arrows in these spaces indicate the course of the beans. That of the round beans is indicated by the lower arrow in the spaces where two arrows are shown, while the upper one indicates the 75 passage of the beans and foreign substances which remain upon the belt. It will be noticed that each successive guide of the pattern L, beginning on the left with the guide L², is set at an angle with the next forward 80 adjacent guide of the pattern M which is more acute than was the last. This adjustment is accomplished by placing each successive guide L' L², &c., in a lower notch m in the adjacent guide of the pattern M than 85 was the last. In this way the path of the beans across the spaces N N² N⁴ N⁶ is turned more directly across the belt in each successive space as the beans progress, thus increasing the tendency to roll them from it. The 90 partition G, hereinbefore described, divides that portion of the inclined surface from which the beans are carried to the chute E' from that portion from which they are carried to the chute E'. Inasmuch as the most perfect beans will be the first to roll from the belt they will be carried to the chute E', while an inferior grade, which will not roll from the belt until they encounter those guides which are set at greater inclination, are turned 95 into the chute E'. Thus the beans are sorted into two grades, and refuse matter and those beans (split and rough) which are below grade are carried off on the belt to the chute H, through which they are discharged. The 100 hopper E' and the portion of the inclined surface F which feeds it are longer in the drawings than the hopper E' and that portion of the inclined surface over it. This proportion of these parts is recommended for 105 the reason that all the beans of the first quality are not as likely to be drawn off from the mass of beans when first spread apart in the spaces N, as is the case in the succeeding spaces, when the number of the beans upon 110 the belt has been reduced, thus permitting 115 their freer movement.

This device is well adapted for separating any objects which are capable of rolling easily when perfect—such as pills, marbles, and 120 shot.

What I claim is—

1. In a separator, the combination of a movable carrier having a plane surface with a fixed path, said carrier being inclined transversely to its line of travel, and guiding means set diagonally to said line of travel and adapted to prevent objects on the carrier from passing under said guiding means, whereby objects capable of rolling roll on the transverse downward incline of said carrier and off the same and other objects are carried 125 130

farther forward on said carrier along said guiding means and are then discharged from the carrier, substantially as described.

2. In a separator, the combination of a movable carrier having a plane surface with a fixed path, said carrier being inclined transversely to its line of travel, and non-yielding guiding means set diagonally to said line of travel and adapted to prevent objects on the carrier from passing under said guiding means, whereby objects capable of rolling roll on the transverse downward incline of said carrier and off the same and other objects are carried farther forward on said carrier along said guiding means and are then discharged from the carrier, substantially as described.

3. In a separator, the combination of a movable carrier having a plane surface with a fixed path, said carrier being inclined transversely to its line of travel, and guiding means set diagonally to said line of travel and adapted to prevent objects on the carrier from passing under said guiding means, whereby objects capable of rolling roll on the transverse downward incline of said carrier and off the same and other objects are carried farther forward on said carrier along said guiding means, said guiding means having such length that the objects so carried farther forward may pass said guiding means on said belt and are then discharged therefrom, substantially as described.

4. In a separator, the combination of an endless belt having a plane surface with a fixed path, said belt being inclined transversely to its line of travel, means for operating said belt, and guiding means set diagonally to said line of travel and adapted to prevent objects on the belt from passing under said guiding means, whereby objects capable of rolling roll on the transverse downward incline of said belt and off said belt and other objects are carried farther forward on said belt along said guiding means and are then discharged from the belt substantially as described.

5. In a separator, the combination of an endless belt having a plane surface with a fixed path, said belt being inclined transversely to its line of travel, means for operating said belt, and non-yielding guiding means set diagonally to said line of travel and adapted to prevent objects on the belt from passing under said guiding means, whereby objects capable of rolling roll on the transverse downward incline of said belt and off the same and other objects are carried farther forward on said belt along said guiding means and are then discharged from the belt, substantially as described.

6. In a separator, the combination of an endless belt having a plane surface with a fixed path, said belt being inclined transversely to its line of travel, means for operating said belt, and guiding means set diagonally to said line of travel and adapted to prevent

objects on the belt from passing under said guiding means, whereby objects capable of rolling roll on the transverse downward incline of said belt and off the same and other objects are carried farther forward on said belt along said guiding means, said guiding means having such length that the objects so carried farther forward may pass said guiding means on said belt and are then discharged therefrom, substantially as described.

7. In a separator, the combination of a movable carrier having a plane surface with a fixed path, said carrier being inclined transversely to its line of travel and a series of stationary guides arranged in zigzag form and set diagonally to said line of travel and adapted to prevent objects on the carrier from passing under said guiding means, each guide having a passage at or near the end thereof nearest to the discharge end of the separator, whereby objects capable of rolling roll on the transverse downward incline of said carrier and off the same and other objects are carried farther forward on said carrier along said guiding means and through said passages and are then discharged from the carrier, substantially as described.

8. In a separator, the combination of a stationary frame, a tilting frame pivoted therein, a roller journaled in each end of said tilting frame, an endless belt upon said rollers, and guiding means set diagonally to the line of travel of said belt and adapted to prevent objects on the belt from passing under said guiding means, whereby objects capable of rolling roll on the transverse downward incline of said belt and off the same and other objects are carried farther forward on said belt along said guiding means and are then discharged from the belt, substantially as described.

9. In a separator, the combination of a stationary frame, a frame pivoted therein and adapted to be tilted both longitudinally and transversely, a roller journaled in each end of said tilting frame, an endless belt upon said rollers, and guiding means set diagonally to the line of travel of said belt and adapted to prevent objects on the belt from passing under said guiding means, whereby objects capable of rolling roll on the transverse downward incline of said belt and off the same and other objects are carried farther forward on said belt along said guiding means and are then discharged from the carrier, substantially as described.

10. In a separator, the combination of an endless belt having a plane surface with a fixed path, said belt being inclined transversely to its line of travel, rollers for said belt, a table for supporting said belt between the rollers, and guiding means set diagonally to said line of travel and adapted to prevent objects on the belt from passing under said guiding means, whereby objects capable of rolling roll on the transverse downward in-

cline of said belt and off the same and other objects are carried farther forward on said belt along said guiding means and are then discharged from the belt, substantially as described.

11. In a separator, the combination of the stationary frame A; the tilting frame B; rollers C C'; table D; belt E; platform F, having the partition G across its surface; and

the consecutive alternating guides L M having the notches l, m, adapted respectively to receive the guides M and L, whereby the angle of the guides L is changed with reference to the line of movement of the belt.

GARDNER A. GIBBS.
